UNITED STATES PATENT OFFICE.

WILLIAM J. BURNETT, OF GLENSIDE, PENNSYLVANIA, ASSIGNOR TO BEAUMONT MANUFACTURING COMPANY, OF PHILADELPHIA, PENNSYLVANIA, A CORPORATION OF NEW JERSEY.

GATE FOR GRAVITY-DISCHARGE HOPPERS.

Application filed June 4, 1926. Serial No. 113,631.

This invention relates to gates for gravity discharge hoppers, more particularly hoppers adapted for reception of hot and incandescent materials, for example hot ashes from boilers of power houses. As a consequence of direct contact with the hot and incandescent materials, gates of the kind referred to are apt to warp, and, as a result, to stick to such an extent as to render their actuation extremely difficult at times.

The main object of the present invention is to overcome the drawbacks mentioned through provision for adequate cooling of the gates, and this desideratum I attain as hereinafter fully set forth, by constructing them hollow, thereby to provide channels for circulation of a suitable fluent cooling medium such as air or water to absorb and dissipate the excess heat.

A further object of my invention is to enable, in instances where quenching is practiced, cooling of the gates to be effected with the quenching water by by-passing the seepage from the hopper for circulation through the hollows of the gates.

In the drawings, Fig. I shows a side elevation of a hopper gate of the pivoted type conveniently embodying my invention.

Fig. II is a rear view of the organization, or, in other words, an elevation as seen as from the right of Fig. I.

Fig. III is a cross sectional view taken as indicated by the arrows III—III in Fig. II.

Fig. IV is a local detail section taken as indicated by the arrows IV—IV in Fig. III; and,

Fig. V is a view similar to Fig. III showing a slight modification of my invention.

With more specific reference to these illustrations, 10 comprehensively designates the hopper, and 11 the gate by which gravity discharge from said hopper is controlled. As shown, this gate 11 comprises a stationary outlet frame member 12 which is flanged as at 13 to enable securing thereof to the hopper discharge opening as by bolts 14; and a movable closure member 15 capable of being swung clockwise (with regard to Fig. I) to open position about a fulcrum axis jointly provided by outwardly projecting trunnions 16 that are journalled in appropriate bearings 17 afforded by the outlet frame member 12, aforesaid. The arcuate

body portion 15^a which provides the closure surface of the movable member 15, is concentrically curved with respect to the fulcrum axis, and counter-balanced for stabilized movement by means of weights 18, secured to the outer ends of rearward projecting arms 19 of the sectoral side pieces 20, 20 between which said body portion is sustained. In the instance shown, the gate 11 is adapted for manual operation and accordingly fitted with a grasp handle 21 having pivotal connection at 22 with the end of a lever arm 23, bolted to one of the weights 18, as illustrated in Figs. I and II. For the purpose of draining away the quenching water seeping from the hopper 10, the organization is equipped with a trough 25 which is sloped downwardly toward the observer in Fig. I, and normally occupies the position shown so as to discharge, by way of a spout 26, into a gutter 27, wherefrom the water is conducted to a suitable point of disposal through a conduit 28. The trough 25 is pivotally mounted to the hopper outlet member 12 at 29, and connected by a link 30 with one of the weighted arms 19, so as to be automatically swung out of the way of the discharge from the hopper 10 when the gate 11 is opened.

The disclosure thus far is of a typical pivoted control gate and chosen for convenience of illustrating the present invention, the novel features whereof I am about to describe. Instead of being constructed solid in accordance with usual practice, the body portion 15^a of the movable gate member 15 is made hollow as shown in Fig. III to permit circulation therethrough of air, water or any other suitable agent, to maintain it cool against warping under the action of heat imparted by virtue of direct contact of its closure surface with the hot and incandescent contents of the hopper 10. The hollow construction of the body portion 15^a of the closure member 15 may obviously be had through integral casting of the same and resorting to coring, but I prefer to provide the same as herein shown, by forming said body portion with a facial depression and by employing a separate renewable cover plate 31 to serve as the closure surface. The plate 31 is supported along opposite ends by integral outstanding flanges 32 of the body portion 15^a, and intermediate

its ends, by a number of embossments 33 allocated at appropriate intervals so as to brace and buttress said plate against indentation. Suitable means such as screws or bolts 34 taking into certain of the embossments may be employed to secure the plate 31 in position. In instances where quenching is practiced, I employ the construction shown in Figs. I-IV from which it will be noted that the plate 31 is perforated to enable the quenching water seepage to enter the hollow of the body portion 15^a and to be thereby conducted or by-passed downwardly through the same and discharged from the lower end into the trough 25 for disposal by way of the gutter 27 and conduit 28. Incidental to circulation through the hollow body portion 15^a of the movable gate member 15, the water will obviously serve to keep the parts sufficiently cool against the contingencies hereinbefore referred to. An upturned lip 35 at the outer end of the plate 31 serves to prevent spill of the water at that region and assists in directing the water into arcuate flow channels 36 (Fig. II) formed in the sectoral side frames 20 of the movable gate member 15.

The described construction is not only advantageous in that it provides for renewal of the closure surface of the gate 11 after extensive wear in use, but enables disassembling for cleaning out, from time to time, of any sediment accumulation of the ash dust in the hollow interior of the gate body portion 15^a.

The modified form of my invention shown in Fig. V is used when quenching is effected dry. In this case the plate 31 is imperforate and the body portion 15^a provided with a number of openings 36 for greater surface exposure of the metal and to enable air circulation freely through its hollow for the purposes of cooling. In all other respects

the modified showing is identical with the first described form, and the corresponding parts are all identified with the same reference numerals to obviate the necessity for repetitive description.

Although I have shown and described my invention as embodied in a pivoted gate 11, the same novel features may be incorporated, with attainment of like advantages, in gates of other types, and the appended claims have purposely been expressed in broad terms with this in mind.

Having thus described my invention, I claim:

1. A gate for gravity discharge hoppers comprising a body portion which provides the closure surface, said body portion having a facial depression with a number of perforations, and a renewable imperforate face plate to form with the facial depression, an internal hollow for circulation of a fluent cooling medium.

2. A pivoted gate for gravity discharge hoppers comprising a shallow concentric arcuate body portion which provides the closure surface, said body portion being hollow and having a series of openings in its bottom for the free circulation of cooling air therethrough.

3. A pivoted gate for gravity discharge hoppers including a shallow arcuate body portion fitted with a removable imperforate cover plate which provides the closure surface, said body portion being hollow and the bottom face perforated to permit entry and free circulation of cooling air, in combination with means to receive and dispose of the seepage water after discharge from the gate.

In testimony whereof, I have hereunto signed my name at Philadelphia, Pennsylvania, this 2nd day of June, 1926.

WILLIAM J. BURNETT.
